[57] CLAIM

The ornamental design for a golf ball display rack, as shown and described.

DESCRIPTION

FIG. 1 is a front elevational view of a golf ball display rack showing my new design, the undisclosed rear is unadorned, and the broken lines shown are for illustrative purposes only, forming no part of the claimed design;

FIG. 2 is a side elevational view thereof with the other side being a mirror image thereof;

FIG. 3 is a top plan view thereof;

FIG. 4 is a bottom plan view thereof; and,

FIG. 5 is a perspective view thereof.
